UNITED STATES PATENT OFFICE.

SEMKO ZADOROZNY, OF ASHLEY, PENNSYLVANIA.

CAR DOOR.

Application filed September 21, 1922, Serial No. 589,563. Renewed October 23, 1924.

To all whom it may concern:

Be it known that I, SEMKO ZADOROZNY, a citizen of Ukraine, residing at Ashley, in the county of Luzerne and State of Pennsylvania, have invented certain new and useful Improvements in Car Doors, of which the following is a specification.

My invention relates to new and useful improvements in car doors and has specific reference to the horizontal sliding type of doors usually employed in freight cars.

The primary object of this invention is the production of a car door that is both simple in operation and inexpensive of manufacture and one wherein the upper and lower edges of the sliding door are provided with a plurality of rollers adapted for rotary engagement within upper and lower channelways provided upon the car body for the easy facilitation of the sliding movement of said door within the channelways.

With the above general object in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a fragmentary side elevational view of a portion of a car body showing my improved form of car door in a closed position and further disclosing one end portion of the lower door guideway being broken away and having a means therein for limiting the outward sliding movement of said car door,

Figure 2 is a fragmentary vertical sectional view upon the line II—II of Fig. 1 and looking in the direction of the arrows,

Figure 3 is a similar view upon the broken line III—III of Fig. 1 and also looking in the direction of the arrows,

Figures 4, 5, 6 and 7 are perspective views of the upper and lower guideways for the sliding car door and the roller carrying means positioned upon the upper and lower sides of the said door, Fig. 6 being partially broken away so as to show the bottom wall of the lower guide channel being provided with a plurality of perforations for purposes hereinafter described, and

Figure 8 is a view in section showing a portion of the floor of the car body having

the lower door guideway associated therewith and disclosing a platform to be received within this guideway for permitting the entrance and exit of the car body of wheeled vehicles or the like, the opposite end of this platform being shown as suitably supported within a wagon or truck.

Referring more in particular to the several views, there is shown a conventional type of freight car body including a roof 1 and floor 2, the said car body being also provided with the usual side walls 3, only one thereof being shown in the drawing.

It is to be understood that each of the side walls 3 of the body is provided with the usual door opening and as a means for closing this opening I have provided the same with an improved type of horizontally sliding door member 4. Adjacent the upper and lower edges of the said side wall opening there is securely fastened upper and lower door guideways 5 and 6 respectively, and it is to be noted that these said guideways are of a length substantially equivalent to twice the width of the car door 4 so as to permit reception of the door therebetween when the same is slid to a position for opening the doorway within the side walls of the car body.

These upper and lower channelways 5 and 6 merely comprise inner and outer spaced flanges 7 and 8 being joined by a cross web 9 and the flange 7 of each of the guideways has a projecting portion 10 formed thereon, which projecting portion is suitably perforated at 11 for receiving bolt fastening means 12 for securely retaining the said guideways to the side walls of the car body. The cross web 9 of the lower guideway 6 is provided with a plurality of perforations 13 for preventing the accumulation of water therein.

The upper and lower edges of the sliding door 4 have the usual reinforcing cross bars 14 secured upon the inner face thereof and secured to the upper and lower marginal portions of the said door are roller carrying brackets 15 and 16, it being noted that the upper roller carrying bracket 15 is so formed as to have the rollers 17 supported therein upon a vertical axis and that the lower roller carrying bracket 16 is formed as to have its corresponding rollers 18 supported upon a horizontal axis. These roller carrying brackets are formed in a manner similar to the channelways 5 and 6 and each

includes spaced walls 20 and 21 joined together by a web portion 22 and the wall 21 of each of the brackets has a projecting portion 23 formed thereon for engagement 5 upon the marginal upper and lower edges of the car door for rigidly securing the same thereto by any desired form of fastening means. The joining web 22 for the spaced walls 20 and 21 of the upper roller 10 carrying bracket 15 is provided with spaced slots 24 for allowing the rollers 17 to project therethrough at which projecting point they are adapted for rolling contact with the outer wall 8 of the upper channelway 15 5. The rollers 18 in the lower carrying bracket 16 are adapted for rolling contact with the cross web 9 of the spaced walls of the lower channelway 6.

Adjacent one edge of the upper and lower 20 guideways 5 and 6 the side wall 3 of the car body is provided with a vertically disposed strip member 25 for preventing disengagement of the door 4 from said channelways in one direction and the connecting 25 webs 9 of the said channelways are provided at their opposite ends with stop blocks 26 for preventing disengagement of the said door from these channel members when being slid in an opposite direction for opening the doorway in the side wall of the car body.

In Fig. 8 I have shown a platform or skid 27 with means adjacent one end as at 28 for reception within the lower channelway 6 when the door 4 is slid to an open position, this skid 27 adapted to extend at one end within the car body for support upon the floor thereof for readily permitting the entrance and exit of a loading vehicle 40 into and from the car for loading or unloading the same. It is to be noted that the opposite end of this skid or platform 27 is to be suitably supported at 29 within a wagon or motor truck. From the above 45 description it will be readily apparent to those skilled in the art that I have provided an improved type of sliding car door wherein any inward or outward thrust upon the same will be readily taken up by the upper

roller members and consequently allow a 50 free sliding movement of the door even though considerable pressure may be maintained thereagainst from the inside of the car and further that the total weight of the door is entirely supported upon the bottom 55 set of rollers also assisting the upper rollers for permitting a free sliding movement of the said door.

Minor changes may be made in the invention without departing from the spirit and 60 scope thereof as claimed.

What I claim is:

In combination with a car body having a side wall provided with a door opening therein, a guideway supported upon said side wall and adjacent one edge of the said door opening, said guideway comprising an inner and an outer flange, a cross-web joining said flanges and a projecting portion 65 extending outwardly from said cross-web having perforations therein for receiving bolt fastening means, the said flanges, cross-web, and projecting portion being formed integrally, a door disposed for horizontal 70 sliding movement in said guideway, rollers and a roller supporting bracket carried by said door and adapted for positioning said rollers above said door on substantially a vertical line therewith, the roller supporting bracket carried by the upper edge of 75 said door comprising a supporting portion secured to the outer face of the door, a perpendicular web portion carried by the supported portion having spaced laterally opening slots formed therein, laterally projecting spaced walls carried by said web portion positioned above said door, and rollers supported upon vertical axes carried by said spaced walls and projecting laterally through 80 said slots and beyond the free edges of said spaced walls to engage the spaced flanges of the guideway for preventing binding of the door caused by inward or outward thrusts placed thereon.

In testimony whereof I affix my signature.

SEMKO ZADOROZNY.
